(57) **CLAIM**

We claim the ornamental design for a sleeve for holding an aerosol generator, as shown.

DESCRIPTION

FIG. 1 is a front perspective view of a sleeve for holding an aerosol generator.

FIG. 2 is a front view of the sleeve for holding an aerosol generator depicted in FIG. 1.

FIG. 3 is a rear view of the sleeve for holding an aerosol generator depicted in FIG. 1.

FIG. 4 is a top view of the sleeve for holding an aerosol generator depicted in FIG. 1.

FIG. 5 is a right side view of the sleeve for holding an aerosol generator depicted in FIG. 1; and,

FIG. 6 is a left side view of the sleeve for holding an aerosol generator depicted in FIG. 1.

1 Claim, 6 Drawing Sheets
